UNITED STATES PATENT OFFICE

138,968

DESIGN FOR A CAPSULE TRAY

Frank L. Wachter, Detroit, Mich.

Application November 9, 1943, Serial No. 111,633

Term of patent 14 years

(Cl. D58—13)

To all whom it may concern:

Be it known that I, Frank L. Wachter, a citizen of the United States, residing at Detroit, in the county of Wayne and State of Michigan, have invented a new, original, and ornamental Design for Capsule Trays, of which the following is a specification, reference being had to the accompanying drawing, forming part thereof.

The tray as shown is transparent.

In the drawing:

I claim:

The ornamental design for a capsule tray, as shown and described.

FRANK L. WACHTER.
